FIG.1.

FIG.2.

INVENTOR
Walter E. Molins

BY
Watson, Coit, Moore & Grindle
ATTORNEY

Patented Nov. 29, 1927.

UNITED STATES PATENT OFFICE.

WALTER EVERETT MOLINS, OF DEPTFORD, LONDON, ENGLAND.

PRINTING MACHINERY.

Application filed March 9, 1927, Serial No. 174,016, and in Great Britain April 1, 1926.

This invention is for improvements in or relating to printing machinery, and more particularly to a printing unit in which an intaglio engraved printing roller is employed.

The present invention consists of a printing unit which comprises in combination a rotatable printing roller, an ink duct arranged to supply ink to said roller, a rotatable furnishing roller spaced apart from said printing roller and arranged to supply ink direct from the duct to said printing roller, and means for driving said furnishing roller from the drive of the printing roller.

Further, the present invention consists of the use, in a printing unit employing a rotatable printing roller, of a furnishing roller having inwardly directed bevelled flanges arranged at either end thereof and adapted to engage with the ends of the printing roller and hold the two rollers in spaced relationship.

The invention is more particularly described with reference to the accompanying drawings, in which:

Fig. 1 illustrates a side elevation of a printing unit constructed according to the present invention.

Fig. 2 is an end elevation of the printing roller, furnishing roller and ink duct of the device illustrated in Fig. 1.

Referring to the drawings which illustrate a printing unit constructed according to British Patent No. 190,202, a web of paper 1 is arranged to receive an impression from an engraved printing roller 2 mounted above an ink duct 3. The engraved roller 2 is arranged to receive ink from a furnishing roller 4 rotatably mounted in the ink duct 3, and the surplus ink is removed from the printing roller by means of a doctor blade 8 in a perfectly well known manner. The furnishing roller 4 is provided at either end thereof with inwardly directed flanges 5 which are arranged to engage with corresponding ends of the printing roller 2 in the manner illustrated in Fig. 2. The bevelled flanges 5 are arranged to engage with the ends of the roller 2 so as to hold the furnishing roller 4 in spaced relationship to the engraved roller 2. The bevelled flanges 5 are mounted upon a spindle 6 so as to be movable axially relatively thereto. In adjusting the position of the furnishing roller 4 the roller

and one flange are moved relatively to the spindle 6 so as to adjust the axial position of the roller 4 to the roller 2, whereupon one of the flanges is screwed upon the spindle 6 so as to correctly space the two rollers apart from one another.

Due to the fact that the faces of the flanges 5 are bevelled, the space between the surface of the furnishing roller and the engraved printing roller may be accurately regulated, and further, the bevelled flanges mounted on the furnishing roller offer very simple and efficient means of driving the furnishing roller by friction from the engraved roller, which offers the advantage of enabling the two rollers to be easily dismantled from the printing unit.

Thus it will be seen that according to the present invention there is provided a furnishing roller adapted to be driven by the engraved roller, without the surfaces of the printing roller and the furnishing roller contacting with one another.

Further, with a furnishing roller of the above character, it is found that the engraved roller is provided with a constant film of ink which is easily removed from the non-engraved portions of the printing roller by means of the doctor blade.

What I claim as my invention and desire to secure by Letters Patent is:

1. A printing unit which comprises in combination a rotatable printing roller, a furnishing roller rotatably mounted in an ink duct and operable to supply ink to said printing roller and a pair of inwardly extending flanges mounted upon said furnishing roller arranged to maintain the same in spaced relationship to said printing roller and adapted to engage frictionally with the ends of said printing roller.

2. A printing unit which comprises in combination a rotatable printing roller, a furnishing roller rotatably mounted in an ink duct and operable to supply ink to said printing roller, a pair of inwardly extending flanges mounted on said furnishing roller so as to be adjustable in an axial direction relatively to said roller arranged to maintain the same in spaced relationship to said printing roller and adapted to engage frictionally with the ends of said printing roller.

In testimony whereof I hereunto affix my signature.

WALTER EVERETT MOLINS.
